(57) **CLAIM**

I claim the ornamental design for a display box with bottles,
as shown and described.

DESCRIPTION

FIG. 1 is a perspective view of a display box with bottles
showing a first embodiment of my new design;

FIG. 2 is a front view thereof;

FIG. 3 is a rear view thereof;

FIG. 4 is a top view thereof;

FIG. 5 is a bottom view thereof;

FIG. 6 is a side view thereof;

FIG. 7 is another side view thereof;

FIG. 8 is a perspective view of a display box with bottles
showing a second embodiment of my new design;

FIG. 9 is a front view thereof;

FIG. 10 is a rear view thereof;

FIG. 11 is a top view thereof;

FIG. 12 is a bottom view thereof;

FIG. 13 is a side view thereof;

FIG. 14 is another side view thereof;

FIG. 15 is a perspective view of a display box with bottles
showing a third embodiment of my new design;

FIG. 16 is a front view thereof;

FIG. 17 is a rear view thereof;

FIG. 18 is a top view thereof;

FIG. 19 is a bottom view thereof;

FIG. 20 is a side view thereof;

FIG. 21 is another side view thereof;

FIG. 22 is a perspective view of a display box with bottles
showing a fourth embodiment of my new design;

FIG. 23 is a front view thereof;

FIG. 24 is a rear view thereof;

FIG. 25 is a top view thereof;

FIG. 26 is a bottom view thereof;

FIG. 27 is a side view thereof; and,

FIG. 28 is another side view thereof.

The broken lines in the Figures are for the purpose of
illustrating unclaimed portions of the display box with
bottles and form no part of the claimed design.

The third and fourth embodiments are shown with a sym-
bolic break in the length of the article. The appearance of
any portion of the article between the break lines forms no
part of the claimed design.
